UNITED STATES PATENT OFFICE.

HERMANN LEMP, OF LYNN, MASSACHUSETTS, ASSIGNOR TO GENERAL ELECTRIC COMPANY,
A CORPORATION OF NEW YORK.

FLUE CONSTRUCTION FOR VEHICLES.

No. 859,568.

Specification of Letters Patent.

Patented July 9, 1907.

Application filed July 27, 1901. Serial No. 69,904.

To all whom it may concern:

Be it known that I, HERMANN LEMP, a citizen of the United States, residing at Lynn, county of Essex, State of Massachusetts, have invented certain new and 5 useful Improvements in Flue Construction for Vehicles, of which the following is a specification.

I have discovered in connection with vaporizers for vehicles, particularly where liquid fuel is employed, that an up or natural draft when properly combined 10 with a down or forced draft, operate very satisfactorily. There is, however, one objection to such an arrangement. Assuming that there is a relatively high wind, and the vehicle has been in operation long enough to have all of the parts hot. If before the fire can be materially checked the vehicle is stopped or caused to move slowly, the wind will blow into the down flue in such a manner that the flames will be driven or spread outwardly, frequently resulting in setting fire to the wood work of the carriage. Many accidents to carriages 15 have occurred which have been caused in this manner. In event of the use of gasolene or other highly inflammable fuel, it sometimes happens that the operator is more or less burned before he or she can jump out of the vehicle. I overcome the objection above 20 pointed out by utilizing a cross or transverse flue which is so connected and disposed with respect to the main flue that wind cannot blow directly down the latter.

A further advantage of my improved construction lies in the fact that the waste products of combustion are 25 conveyed to the sides of the vehicle, and there allowed to escape, thus reducing the liability of damaging the canopy of the vehicle in case it is down. This also tends to prevent the gases from annoying the occupants of the vehicle.

30 In the accompanying drawings which illustrate an embodiment of my invention, Figure 1, is a perspective view of a vehicle body showing the vaporizer in place. Fig. 2, is a perspective view of a part of the vehicle body showing the cover for the inclosing case raised, 35 to permit inspection of the boiler. Fig. 3, is a perspective view of the boiler, and Fig. 4 is a vertical section thereof with the cross-flue in position to receive the productions of combustion.

1, represents the vehicle body which is extended 40 rearwardly as at 2, to form an inclosing box or casing for the steam generator 3. The casing 2, is provided with a hinged cover 4; which may be raised or lowered at will to inspect the boiler.

For convenience of illustration, as representing one 45 type of boiler and burner I have shown a flash boiler and a kerosene burner, but my invention is not to be construed as being limited to the use of any particular kind of boiler or burner or combination thereof. The boiler proper consists of a pipe 5, which is bent into 55 any convenient shape, and is inclosed by a suitable

casing 6. Between the layers or grids of pipe spaces are formed which act as flues for the fire gases. Below the boiler tubes, which are supported in any suitable manner, is located a cylindrical body of fire-brick 7. This forms a part of the fire-chamber and surrounds the 60 burner, which burner, in the present instance, consists of a nozzle 8, baffling plate 9, and a vaporizer 10. The necessary air to support combustion enters by means of the holes 11, which are located near the corners of the casing 6. The air in passing downward, 65 around the cylindrical fire-brick lining 7, becomes more or less heated thereby adding to the economy of the system. The bottom of the boiler casing is closed by the plate 12, and is provided with a small door 13, through which an igniter may be inserted or the burner 70 inspected. Extending across the top of the boiler casing is a plate or partition 14; this partition is provided with an opening 15, through which the fire gases, indicated by the arrows, are free to pass. In the upper end of the casing between the partition and the top is 75 formed a chamber 16, which chamber is provided at the rear with a short upwardly extending flue 17, and this in turn engages with the flue 18, carried by the cover 4, of the vehicle body. The chamber also opens into the down flue as will appear hereinafter. I may 80 dispense with the partition 14 and permit the fire gases to pass directly out the up and down flues, the action of the cross flue being the same in both cases. In using the word "chamber" I do not mean to restrict myself to the structure shown wherein a portion of the casing 85 is actually divided off, but use it in a broader sense as meaning a space wherein the fire gases mingle more or less freely before passing through the flues.

The flue 18, may be secured to the cover in any suitable manner, and is provided with an open ended cross 90 or transverse flue 20, consisting of two substantially horizontal divergent branches, each branch in the present instance is shown as being semi-circular in outline, but any other form may be substituted if desired. The flue 20 extends transversely of the vehicle body and 95 terminates at or near the side walls thereof. The flue 17, is rectangular in outline as will readily be seen in Fig. 3, and the flue 18, is of corresponding shape and just enough larger so that the cover 4, may easily be raised, as is illustrated in Fig. 2. The cross flue 20, is 100 made somewhat longer than the flues 17 and 18 so that no opportunity will be afforded for a gust of wind to blow down through the flues 18 and 17, and flues between the boiler tubes into the fire chamber and cause the flames to be forced outward through the air admitting openings 11, or through any other opening or openings in the boiler casing which are made intentionally or otherwise. By making the cross flue 20, somewhat longer than the flue 18, the waste products of combustion are carried to the sides of the vehicle, so that they 110

will not annoy the occupants either when the vehicle is standing still or moving slowly. It also prevents the hot gases from scorching the canopy of the vehicle when it is lowered.

5 The chamber 16, formed in the upper end of the boiler casing besides opening upward is provided with an opening 21, which communicates with a vertically extending flue 22, that creates the down or forced draft when the vehicle is in operation. This flue is preferably made of sheet metal and is secured to the side of the boiler casing 6, as is indicated in Fig. 3. The flue is closed at its upper end 23 but is open at the lower end, as is indicated in Fig. 4. Passing through the chamber 16, is the exhaust pipe 24, from the engine, which is 10 turned downwardly, as is indicated in dotted lines, at the point where it enters the flue 22. As soon as the vehicle is started into operation, and exhaust steam passes through the exhaust pipe and into the down flue, the draft is materially increased and the waste products of 15 combustion, instead of passing out through the vertical flues 17 and 18, and through the cross flue 20, pass out through the downwardly extending flue 22, and are projected toward the roadbed. The length of the flue 22, and also that of the cross flue 20, can be varied to suit 20 the vehicle to which the apparatus is applied. By mounting the cross flue 20, on the cover 4, of the vehicle body, a very convenient arrangement is provided whereby the boiler and the other parts of the vehicle may be inspected. It will be seen that the parts are so 25 arranged that the wind cannot blow directly down through the vertical flues 18 and 17, into the chamber 16, thence to the fire-box, neither can any waste products of combustion pass through the flues and strike the vehicle canopy, in case such a canopy is used, for they 30 will be deflected across to the side of the vehicle.

What I claim as new and desire to secure by Letters Patent of the United States, is,

1. In combination, a boiler, a burner, a casing therefor, a chamber formed in one end of the casing, a flue opening 40 downward out of the chamber from one point, a second flue opening upward out of said chamber from another point, and an open ended cross flue which engages with the upper end of the upwardly extending flue for carrying off the waste products of combustion.

2. In combination with a steam generator, a burner, a casing therefor having a chamber above the generator, a flue communicating with the chamber and through which steam and fire gases from the chamber pass under ordinary running conditions, a second flue communicating 50 with the chamber independently of the first and through which the fire gases pass when the generator is being started into operation, and a transversely extending flue which is connected to the last mentioned flue to prevent drafts of air from spreading the burner flame.

3. In combination, a vehicle body provided with an opening, a boiler located within the body, a flue for the boiler which communicates with the opening in the vehicle body, a transversely extending flue which communicates with said opening and receives fire gases from said flue, and a third flue which extends downwardly below the vehicle body and is arranged at its upper end to receive fire gases independently of the first mentioned flue and discharge them below the body.

4. The combination of a boiler, a casing, a flue for 65 creating an up draft, a connection between the exhaust port of the engine and the casing, a second or transverse

flue connected with the first, and a third or down flue which communicates with the casing independently of the first flue.

5. In combination, a vehicle body, a boiler inclosed by the body, an upwardly opening flue, a cover for the body of the vehicle which covers the top of the boiler, a flue mounted on the cover which engages with the opening in the boiler, and a transversely extending flue which is also carried by the cover and is in free communication with the flue opening.

6. In a vehicle, the combination of a body having a rearwardly extending portion which incloses the boiler, a cover for said portion, a boiler, a casing for the boiler containing upwardly and downwardly opening flues, and a transversely extending flue which is mounted on and over the said cover and is so arranged that it is in communication with the upwardly opening flue.

7. In combination, a boiler, a casing therefor having a chamber above the boiler, a burner, an upwardly extending flue which opens upward from the casing, a transversely extending flue arranged to engage with the first flue, and a third flue which has an opening at its lower end and communicates at its upper end with the casing at a point above the boiler and independently of the first mentioned flue.

8. In a vehicle, the combination of a body, a boiler, a burner, a cover on the body located above the boiler, and a flue which is mounted on the cover for carrying off the fire gases.

9. In a vehicle, the combination of a body, a boiler, a burner, a cover on the body, a vertically extending flue mounted on the cover and arranged to carry off the fire gases, and a transverse flue which opens into the first and is also carried by the cover.

10. The combination with a carriage body, of a steam-boiler carried thereby and having a burner for heating it; and a flue for disposing of the products of combustion from the burner, said flue having substantially-horizontal divergent branches located exterior to the carriage body, which are provided with outlets to the atmosphere and are arranged on either side of that portion of the flue which is located within the carriage body and connects with the flues or heating-passages of the boiler, said branches together forming a through-passage for disposing of atmospheric currents which might otherwise reverse the normal draft of the burner.

11. The combination with a carriage-body and a cover therefor, of a steam-boiler carried by the body and located below the cover, a burner for heating it, and a flue for disposing of the products of combustion from the burner, said flue having substantially-horizontal divergent branches extending transversely of and over the carriage-body cover and terminating in outlets to the atmosphere which coincide substantially with the planes of the side walls of the carriage-body, said branches being arranged on either side of that portion of the flue which connects with the flues or heating-passages of the boiler, and together forming a through-passage for disposing of atmospheric currents which might otherwise reverse the normal draft of the burner.

12. The combination of a vehicle body, a seat, a boiler within the body which is located below the level of the seat, a flue extending from the boiler from a point interior to a point exterior to the body, and a horizontal flue located exterior to the body which is open at both ends and connected at an intermediate point to the first-mentioned flue so that the fire gases can pass off from either or both of the open ends.

In witness whereof I have hereunto set my hand this 23rd day of July, 1901.

HERMANN LEMP.
